UNITED STATES PATENT OFFICE.

CHARLES SEYMOUR, OF DEFIANCE, OHIO, ASSIGNOR TO THE DEFIANCE MACHINE WORKS, OF SAME PLACE.

SWING-SAW.

SPECIFICATION forming part of Letters Patent No. 427,196, dated May 6, 1890.

Application filed January 4, 1890. Serial No. 335,873. (No model.)

To all whom it may concern:

Be it known that I, CHARLES SEYMOUR, a resident of Defiance, in the county of Defiance and State of Ohio, have invented certain new and useful Improvements in Swing-Saws; and I do hereby declare the following to be a full, clear, and exact description of the invention, such as will enable others skilled in the art to which it appertains to make and use the same.

My invention relates to an improvement in swing-saws, the object being to provide a spring-balance which will compensate for the resistance opposed by gravity to the extreme of swing of the saw.

With this end in view my invention consists in certain novel features of construction and combinations of parts, as will be hereinafter described, and pointed out in the claims.

In the accompanying drawings, Figure 1 is a front elevation, and Fig. 2 is a side elevation.

A represents a hanger depending in the usual manner from the ceiling, where it is securely bolted, and 1 is an arm hung on a shaft 2, which connects the hanger and swing-arm pivotally together. In boxes 3 3, formed at the terminus of the swing-arm 1, a shaft 4 is revolvably supported, and on the outer end of this shaft the circular saw 5 is secured. An endless belt 6, passed over the drums 7 and 8, located on shafts 2 and 4, respectively, communicates motion from the former to the latter, whereby the saw is rapidly rotated, and shaft 2 is provided with loose and fixed pulleys 9, over one of which a drive - belt is passed, accordingly as it is desired to impart motion or not to the shaft 2.

To compensate for the resistance opposed by gravity to the extreme of swings of the arm 1, a pair of pivoted equalizers 10 and 11, having yielding connection with each other, are resorted to. The lower equalizer 11 is pivoted to the arm 1, and the upper one 10 is suspended by means of a link 12 from the adjustable eyebolt 13, and said eyebolt is held in place by a set-screw 14, or by similar means. By this arrangement the equalizer 10 may be supported coincident with the center of suspension, or on either side of the hanger and any distance therefrom, the object being to

normally incline the arm 1 to one side or the other or to retain it in a vertical position, as most convenient. A pair of spiral springs 15 are held in suspension between the ends of the equalizers by means of rods or stems 16 and 17, and the tension of these springs is regulated by turning the nuts 18 on the stems 16. In lieu of the two springs one spring could be made to accomplish the same result by attaching it outside of the hanger.

The reason for using the system of equalizers and connections, as shown in the drawings, is to permit attachment closer to the arm 1.

It is evident that slight changes might be resorted to in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. In a swing-saw, the combination, with a swing-arm, of a spring connected with said arm for retaining it yieldingly in position, and means for shifting laterally the point of suspension of the spring, substantially as set forth.

2. In a swing-saw, the combination, with a hanger and a swing-arm hung thereon, of a pair of equalizers, one supported on the hanger and the other on the arm, and springs connecting the ends of these equalizers, substantially as set forth.

3. In a swing-saw, the combination, with a hanger and a swing-arm hung thereon, of a pair of equalizers, one pivoted on the arm and the other adjustably supported on the hanger, springs connecting the outer ends of the equalizers, and means for regulating the tension of the springs, substantially as set forth.

In testimony whereof I have signed this specification in the presence of two subscribing witnesses.

CHARLES SEYMOUR.
